DESIGN FOR A SOUVENIR BLOCK FOR CARRYING ADVERTISING MATTER

Thadeus K. Podwyszynski, Brooklyn, N. Y.

Application December 29, 1938, Serial No. 82,042

Term of patent 3½ years

To all whom it may concern:

Be it known that I, Thadeus K. Podwyszynski, a citizen of the United States, residing at Brooklyn, in the county of Kings and State of New York, have invented a new, original, and ornamental Design for a Souvenir Block for Carrying Advertising Matter, of which the following is a specification, reference being had to the accompanying drawing, forming part thereof.

In the drawing:

Fig. 1 is a perspective view of a souvenir block for carrying advertising matter, showing my new design.

Fig. 2 is a side view thereof, and

Fig. 3 is an end view.

I claim:

The ornamental design for a souvenir block for carrying advertising matter, as shown.

THADEUS K. PODWYSZYNSKI.
